(57) **CLAIM**

The ornamental design for a holding stand for incorporating surveillance camera as shown and described.

DESCRIPTION

FIG. 1 is a perspective view of the holding stand for incorporating surveillance camera, showing our new design; FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings illustrate portions of the holding stand for incorporating surveillance camera and form no part of the claimed design.

1 Claim, 7 Drawing Sheets
